UNITED STATES PATENT OFFICE

GEORGE C. BROWN, OF WORCESTER, MASSACHUSETTS

HUMIDIFYING APPARATUS

Application filed May 28, 1931. Serial No. 540,701.

This invention relates to apparatus for humidifying the air in a dwelling-house and in other buildings heated by steam or hot-water. It is well known that the air in such buildings is commonly lacking in moisture, and that a substantially lower temperature will be found comfortable and satisfactory if the moisture content of the air is increased.

It is the general object of my invention to provide an improved and more effective humidifying apparatus for such purposes, which apparatus may be easily manufactured and installed and which will be found reliable and satisfactory in use.

With this general object in view, important features of the invention relate to the provision of removable evaporating units of an improved design and construction, and to the provision of improved means for supplying moisture to said evaporating units.

My invention further relates to arrangements and combinations of parts which will be hereinafter described and more particularly pointed out in the appended claim.

A preferred form of the invention is shown in the drawing, in which

Fig. 1 is an end elevation of a steam or hot-water radiator having my invention applied thereto;

Fig. 2 is a side elevation of the radiator and humidifying apparatus, looking in the direction of the arrow 2 in Fig. 1;

Fig. 3 is a partial perspective view of the water supply and spray pipes;

Fig. 4 is a side elevation of one of the evaporating units with a portion of the covering broken away, and

Fig. 5 is an end view of one of the upper evaporating units, looking in the direction of the arrow 5 in Fig. 2.

Referring to the drawing, I have shown a radiator R of an ordinary commercial design and formed of sections, each having a plurality of openings 10 formed therein. These openings are arranged in parallel vertical series and are aligned in the different sections to provide continuous passages through the full length of the radiator.

My improved evaporating units E are placed in the aligned openings 10. Each unit

E preferably comprises a bag or casing 20 of some suitable woven material, preferably linen, and an open frame-work 21 adapted to be inserted in the bag or casing 20 and to hold the same in flat distended condition. 55

The frame-work 21 may conveniently be provided with a handle portion 22 at one end, by which insertion and removal of the evaporating unit in the opening 10 is facilitated.

The moisture for the evaporating units E is provided by a supply pipe 30 (Fig. 2) which may be in the basement of the building and may be connected to the usual water main. I have shown the supply pipe 30 as 65 connected to a shut-off valve 31, a filter 32, and a reducing valve 33, all of usual commercial construction.

A pipe 34 leads upward from the reducing valve 33 to a needle valve 35, and a pipe 36 70 extends upward from the needle valve 35 to a fitting 37 connected to forked or branched spray pipes 38.

One of these spray pipes 38 is provided for each vertical series of openings 10 in the 75 radiator R. These spray pipes 38 are provided with suitable small openings, spaced throughout their length and delivering water in the form of drops or a fine spray to the evaporating units. 80

Preferably, the casing 20 of each upper evaporating unit E is provided with a small opening at the closed end of the casing, permitting the casing to be slipped over the free end of a spray pipe 38, so that the spray pipe 85 is disposed within the casing, as clearly shown in Fig. 5.

Having described the details of construction, the operation and advantages of my improved humidifying apparatus will be 90 readily apparent. The reducing valve 33 provides low pressure water for the needle valve 35, which may be set to allow the water to pass through the valve at any desired slow rate. This water is distributed through the 95 spray pipes 38 to the upper evaporating units E and the surplus water drips down to the lower evaporating units.

If the radiators are cool or if for any other reason the water is not all evaporated, the 100

surplus water drips into a pan 40 which is placed on the floor under the radiator R and which may be connected to a suitable waste-pipe 41.

5 The apparatus as above described possesses several important advantages. It provides a continuous and definite supply of water for evaporative purposes, which water is distributed under conditions most advantageous for 10 evaporation. The linen casings 20 readily receive this water and hold it closely adjacent to the hot radiator surfaces. The evaporating units E may be readily removed when desired and the casings 20 may be easily 15 slipped off of the frames 21 for washing or replacement.

20 The entire apparatus is very easily installed in any radiator having one or more longitudinal and vertical openings and is scarcely visible after installation. The apparatus operates continuously without personal attention, and very substantially increases 25 the moisture content of the air where the apparatus is used.

25 The amount of moisture delivered may be varied and controlled by changing the setting of the needle valve, so that any desired 30 humidity may be maintained. Any usual automatic control for the needle valve may be provided.

35 Having thus described my invention and the advantages thereof, I do not wish to be limited to the details herein disclosed, otherwise than as set forth in the claim, but what I claim is:—

40 A humidifying apparatus for a radiator having openings extending vertically and longitudinally between spaced portions of said radiator and arranged in a plurality of superposed series, said apparatus comprising a plurality of evaporating units positioned in corresponding superposed series in said openings, a spray pipe through which water is fed continuously and at a predetermined rate to the upper evaporating unit of each series, means to provide a continuous supply of water to said spray pipe from a separate source outside of and disassociated from said radiator, 45 and manual means to regulate the flow of water to said spray pipe, each lower evaporating unit in said series being positioned to receive the unevaporated moisture of the next higher unit and to further the evaporation thereof, and each evaporating unit being separately insertable and removable from operative position in its radiator opening.

50 In testimony whereof I have hereunto affixed my signature.

60 GEORGE C. BROWN.
